MULTIPLE VALVE

Roy L. Lay, Rocky Ford, Colo.

Application April 24, 1950, Serial No. 157,683

2 Claims. (Cl. 277—20)

1

This disclosure has reference to a multiple discharge valve, and while adaptable for many uses, it is more particularly designed for use on the spray pipes of sugar centrifugals. Spray pipes in sugar centrifugals extend vertically within the whirling screen and are provided with a plurality of vertically spaced sprays for washing the sugar crystals on the screen. The usual spray pipe has been troublesome due to the fact that when the water is shut off, the entire pipe will drain through the lowermost sprays so as to place more water on the lower crystals than on the upper, resulting in either a non-uniform washing or a wasteful dissolving of sugar crystals.

The principal object of this invention is to provide a valve structure for spray pipes in which every spray along the pipe will open and close individually and simultaneously so as to prevent certain sprays from operating after the others have ceased, and to prevent drainage through the lowermost sprays.

Another object of the invention is to provide a single operating member for simultaneously operating a plurality of valves.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a fragmentary side view, partially in section, of a typical spray pipe with the invention incorporated therein, illustrating the valves in the closed position;

Fig. 2 is a cross-section, taken on the line 2—2, Fig. 1;

Fig. 3 is a similar cross-section, taken on the line 3—3, Fig. 1;

Fig. 4 is a detail, perspective view of the valve member in the invention; and

Fig. 5 is a fragmentary section, taken on the line 5—5, Fig. 3, illustrating the valve in the open position.

The invention is built into a spray pipe 10 extending downwardly from a T-fitting 11, through which fluid is supplied to the spray pipe from a supply pipe 32. The lower extremity of the spray pipe is closed by means of a threaded plug 33. A plurality of cross tubes 12 extend through the spray pipe 10 at spaced-apart intervals. 55 nut 30.

2

The cross tubes are of smaller diameter than the spray-type pipe 10, and project from both sides of the latter. These cross tubes are soldered, brazed, or otherwise sealed to the spray pipe 10. 5 They could, of course, be formed integrally with the spray pipe if preferred.

One extremity of each cross tube is externally threaded to receive a spray nozzle cap 13. The other extremity is internally threaded to receive a threaded plug 14. The spray extremity of each tube is formed with a spray port 15 of smaller diameter than the remainder of the tube so as to form a tapered valve seat 16.

A valve member 17 is slidably mounted in each cross tube 12. The valve members are formed with a tapered valve point 18 adapted to close the tapered seats 16. One side of each valve member 17 is cut away intermediate its extremities to form an elongated side notch 19 therein. 20 The inner extremity of each side notch is rounded, as indicated at 20.

The valve members 17 are provided with screw driver slots 21 into which a screw driver or similar tool may be inserted for rotating the valve 25 to grind or lap it to its seat. The pointed extremities 18 of the valves 17 are constantly urged against the seats 16 by means of compression springs 22 acting against the plugs 14.

The tubes 12 are longitudinally slotted, as indicated at 23, on their upper end lower sides for the passage of a cam bar 24 which extends through the side notch 19 of each valve member 17. The forward edge of the cam bar 24 is straight. The rearward edge, however, is inclined at intervals, as shown at 25, to form narrow portions 26.

When the narrow portions 26 of the cam bar are opposite each of the valve members 17, the latter will be released so that the springs 22 may force them to their seats. When the wide portions of the cam bar 24, however, are forced opposite the valve members, the inclined portions 25 of the cam bar will act against the rounded ends 20 of the notches 19 to force the valve members 17 from their seats against the action of the springs 22 as shown in Fig. 5.

The cam bar 24 is reciprocated by means of a valve stem 27 formed on one extremity of the bar and connected with any suitable handle or other operating mechanism (not shown). The valve stem 27 passes through a terminal plug 28 threaded into the upper extremity of the T-fitting 11, and is sealed against leakage by means of suitable packing 29 and packing 50 nut 30.

Discharge passages 31 are drilled in each tube 12 adjacent the valve seat 16 to allow fluid to flow from the pipe 10 to the spray port 15 when the valve member is withdrawn, as shown in Fig. 5.

It can be readily seen that when the cam bar 24 is in the position of Fig. 1, all of the sprays along the spray pipe will be closed. It can also be seen that if the cam bar 24 is pulled upwardly, all of the sprays will be opened simultaneously. This prevents the fluid from the spray pipe from draining through the lowermost sprays thereon when the cam bar is in the closed position of Fig. 1.

While a specific form of the improvement has been described and illustrated herein, it is to be understood that the same may be varied, within the scope of the appended claims, without departing from the spirit of the invention.

Having thus described the invention, what is claimed and desired secured by Letters Patent is:

1. A multiple valve structure comprising: a pipe; a plurality of cross tubes extending through said pipe at spaced-apart intervals; a valve seat in one extremity of each tube; a valve member in each tube positioned to close said valve seat; a spring in the other extremity of each tube urging the valve member therein toward its seat, there being elongated openings in the top and bottom of each tube, and there being a notch formed in the side of each valve member; a cam bar extending longitudinally within said pipe through the openings in said tubes and through the notches in said valve member; and inclined cam surfaces on said bar adapted to contact the extremities of said notches when

said bar is moved in one direction to force said valve members from their seats.

2. A multiple valve structure comprising: a pipe; a plurality of cross tubes of smaller diameter than said pipe extending diametrically and completely through said pipe at spaced-apart intervals, both extremities of each tube projecting outwardly from said pipe; a valve seat in one extremity of each tube; a valve member in each tube positioned to close said valve seat; a spring in the other extremity of each tube urging the valve member therein toward its seat, there being elongated openings in the top and bottom of each tube, and there being a notch formed in the side of each valve member; a cam bar extending longitudinally within said pipe through the openings in said tubes and through the notches in said valve member; and inclined cam surfaces on said bar adapted to contact the extremities of said notches when said bar is moved in one direction to force said valve members from their seats.
